UNITED STATES PATENT OFFICE

142,632

DESIGN FOR AN ELECTRIC LIGHT FIXTURE

Edward Erger, Los Angeles, Calif., assignor to
Robert S. Herman, Los Angeles, Calif.

Application January 15, 1945, Serial No. 117,432

Term of patent 3½ years

(Cl. D48—4)

To all whom it may concern:

Be it known that I, Edward Erger, a citizen of the United States, residing at Los Angeles, in the county of Los Angeles and State of California, have invented a new, original, and ornamental Design for Electric Light Fixture, of which the following is a specification, reference being had to the accompanying drawing, forming a part thereof.

The figures in the drawing are as follows:

Fig. 1 is a front view of an electric light fixture showing my new design;

Fig. 2 is a side elevational view thereof;

Fig. 3 is a top plan view thereof.

The dominant features of my design reside in the portions shown in full lines.

I claim:

The ornamental design for an electric light fixture, as shown and described.

EDWARD ERGER.
